UNITED STATES PATENT OFFICE

2,534,416

TEMPERATURE CONTROL APPARATUS

Linvell Arnett Cox, Chicago, Ill., assignor to Minneapolis-Honeywell Regulator Company, Minneapolis, Minn., a corporation of Delaware

Application September 28, 1946, Serial No. 700,095

6 Claims. (Cl. 236—49)

1

The present invention relates to self-contained automatic air flow controlling registers for air conditioning systems.

It has long been considered that automatic individual room control for air conditioning systems is most desirable but the prior art apparatus capable of giving the desired results is generally complicated and costly.

It is therefore an object of this invention to provide improved apparatus for individual room control of air conditioning systems.

It is also an object to provide an improved self-contained automatic air outlet control capable of controlling air flow in response to room temperature.

It is an additional object to provide an improved automatic register for air conditioning systems that functions equally well on either a heating or a cooling sequence.

It is a further object to provide an automatic self-contained register which is readily adjusted for either heating or cooling control and which has a readily adjusted control point for either sequence.

It is also an object to provide an automatic self-contained register having means for readily connecting in or disconnecting the automatic mechanism from operative relation and permitting the manual closing of the said register.

It is another object to provide a register of the sort described which is simple and dependable, adapted for mass production and easily installed.

These and other objects will become apparent upon a study of the following specification and drawings wherein:

Figure 1 is a sectional elevation view taken on line 1—1 of Figure 2.

Figure 2 is a front elevation, with parts in section, taken on the line 2—2 of Figure 1.

Figure 3 is a partial front elevation view showing a detail.

Figure 4 is a plan view of a portion of the present mechanism with parts in section taken on the line 4—4 of Figure 2.

The present control devices or registers are used on the outlets of ducts supplying conditioned air to rooms or other spaces, and control the flow of air through the individual ducts in response to the temperatures sensed by the thermostatic means of the respective registers.

The basic register used in the present invention is preferably of the sort having movable shutter or damper blades arranged to provide a uniform direction of air flow and to cause good aspirating effects at all degrees of opening. The

2

device 10 shown is of this type but for a fuller description of this sort of register, reference is made to the copending application of Hermanson and Joesting, Serial No. 656,274, filed March 22, 1946.

5 The register 10 may include a housing 11 having a downwardly extending portion 12 arranged to be connected to a duct, not shown, or may have its parts arranged to be inserted in an existing housing or the like. The register portion proper includes a transversely arranged section 13 extending out through an opening in the wall 14 and having a discharge opening 15. Blades 16 and 17 are hingedly mounted to casing 13 and are connected for simultaneous operation by link 18, 19 and 20. Vertically arranged vanes 24 are adjustable to give the desired distribution of air within the space being treated, as more fully explained in the aforementioned application. However, this feature forms no part of the 10 present invention. While the register structure shown, and as described in the said application, is the preferred form to use, it will be obvious upon a full consideration that the present invention can be used with any conventional register structure that provides a good aspirating effect on the air being treated.

15 Pivoted lever 23, which is connected to lever 21 of blade 17 by link 22, forms part of an operating mechanism for the present device generally designated as 25. Operating mechanism 25 is assembled on a U-shaped frame 26 of a suitable material such as strip steel and includes vertical legs 27 and 28 and a horizontal connecting portion 29. The frame 26 is connected to housing 11 or other suitable structural part of the register by means such as brackets 30, one of which is shown, connected between the aforementioned legs and section 13 of said housing 11. The mechanism 25 includes a vertically movable shaft 31 actuated by a bellows 32, the bellows exerting a variable force upwardly on the said shaft 31. Shaft 31 is guided in its vertical movements by flexible reed means 33 and 34 suitably attached to leg 28 of frame 26. The pressure for expanding bellows 32 is generated by a temperature responsive bulb 35 connected to bellows 32 by a capillary tube 36, the bulb 35 being located below the projecting portion 13 of the register and on the room side of wall 14. Bulb 35 is secured to section 13 by 20 means not shown and is concealed and shielded by a trim strip means 38 having openings 39 in its bottom portion and openings 40 in its upper portion. In the normal operation of the register, the discharged air tends to aspirate the room air 25 in a manner to cause a flow of air up along the

surface of wall 14 which then merges with the discharge flow. A portion of this aspirated air flows through openings 39, around bulb 35 and out through openings 40, thus permitting the said bulb to respond to room temperature. As the present device is intended for the control of both heating and cooling air, bulb 35 is charged with a cross ambient type fill so that control of the instrument is always exercised by said bulb. The reason for this is explained by the presence, under all normal circumstances, of a liquid evaporating surface in the bulb. Obviously, with an increase in temperature at bulb 35, the pressure in bellows 32 is increased, thus tending to move shaft 31 upwardly, whereas a decrease in temperature at bulb results in a decreased force exerted on shaft 31 by bellows 32 thus permitting the forces opposing bellows 32 to move shaft 31 downwardly.

The force opposing bellows 32 is principally caused by a lever means 44 which bears against a knife edged pivot means 45 carried by shaft 31, and which lever is fulcrumed at its right end by a pivot means generally designated as 46. A suitable weight 41 is attached to the left end of the said lever means 44 and tends to rotate the same about pivot means 46 in a manner to force shaft 31 downwardly. The pivot means 46 includes a roller 47 pivotally mounted in a frame 48 built up on link means 49. Link means 49 is pivoted to a link 50 which in turn is pivotally mounted on bracket 51 attached to leg 27 of frame 26. Link 49 is also pivotally attached to a rotatable arm 52 which is attached to a vertical rotatable shaft 53 mounted on leg 28 of the said frame 26. Rotatable shaft 53 extends to the upper portion of the device and is there connected to an adjusting and indicating lever 55 which operates in slot 56 of a suitable scale plate 57. To protect lever 55, a cover member 58 is arranged to form a part of the housing structure 11. As shown in Figure 1, a suitable trim strip 59 is arranged between cover 58 and wall 14 at the upper portion of the apparatus.

As will be obvious upon inspection, rotation of shaft 53 and arm 52 moves the pivot means generally designated as 46 along the right end of lever means 44, the frame 48 of the said pivot means being guided by bracket means 54 attached to leg 28 of frame 26. As the pivot means 46 is adjusted toward shaft 31, weight 41 has an increased effect in opposing the force exerted by bellows 32 on shaft 31, whereas, when the pivot means 46 is moved to the right end of lever means 44, weight 41 has less effect in opposing the forces due to bellows 32 on the said shaft 31, the difference in effect being due to the difference in the leverage ratios of the mechanism. While a weight 41 is shown, it is obvious that a suitable spring may be substituted for the said weight. A weight is used because of its lack of a spring rate which thus permits a very low operating differential for the instrument. However, as is obvious to those skilled in the art, the operating differential may also be kept suitably low by using a compensated spring means for opposing the bellows 32.

Lever 23 is pivotally mounted at 60 to shaft 31, hence the pivot portion at least of the said lever is moved vertically upon movement of the said shaft. Lever means 23 is in the form of a double bell crank and has oppositely arranged crank portions 61 and 62. A clutch link means 63 having an outwardly directed V-notch 64 is pivoted at 65 to crank portion 61 while a similar clutch link 66 having a V-notch 67 is pivoted at 68 to crank portion 62. Notches 64 and 67 are so

proportioned that the vertical distances between their outer edges is at least equal to the vertical travel of shaft 31. The inner opposed edges of link means 63 and 66 are engageable with a bearing 70 which is carried by a bracket 71 attached to leg 27 of frame 26. Bracket 71 includes horizontally disposed guide portions 72 and 73 having slots 74 and 75, respectively.

A slide member 76 including bent-over portions 77 and 78 is slidably mounted on extensions 72 and 73 of bracket means 71 by pin means 79 and 80 extending through slots 74 and 75, respectively. Pin means 79 and 80 not only slidably guide means 76 but also limit the travel of the same. Bent over portion 77 of slide 76 has an inwardly directed V or wedge shaped portion 81 directed toward link means 63 whereas bent-over portion 78 includes a similar V or wedge shaped portion 82 shown in mating engagement with notch 67 of link 66.

The V-shaped portions 81 and 82 are spaced apart a sufficient distance such that portion 82 may engage notch 67 as shown when slide means 76 is in its extreme left position. When moved to the right a sufficient distance, portion 82 may disengage from link 66 without portion 81 engaging link 63 but when moved still further to the right, to the extreme of travel of the slide means 76, portion 81 will then be in mating engagement with notch 64 of link 63, bearing means 70 preventing either link 63 or 66 from moving away from its respective engaging means. By proportioning notch means 64 and 67 so that the vertical distance between the outer edges of the said notches is at least equal to the full travel of shaft 31, either wedge-shaped portion 81 or 82, upon engaging the respective notch portion in link 63 or 66, may force the respective link to move sufficiently to permit a full and proper mating engagement of the notch with the wedge-shaped edge of the slide means.

In the position shown, with link 66 locked against vertical movement, lever 23 will obviously be rotated in a clockwise direction about pivot 68 by an upward movement of shaft 31 with, of course, a reverse rotative movement upon a downward motion of the said shaft. When wedge portion 81 is in mating engagement with notch 64 of link 63, so that link 63 is fixed against movement and link 66 is free to move vertically, a similar upward movement of shaft 31 will result in a counterclockwise movement of lever 23, with a clockwise movement being caused by a downward movement of shaft 31.

Slide means 76 is adjusted by a connecting member 84 attached to a cylindrical tubular member 85 having a cam slot 86. A rotatable plug 87 having a pin 88 engageable in the slot 86 is rotatably mounted in the said tubular means 85 and is journaled at 89 in a suitable portion 90 of the register housing structure. Plug means 87 is rotated by a suitable key and indicating means 91 which is essentially non-circular in shape but has a suitable circular necked down portion at the journal 89. Rotation of key means 91, resulting in a rotation of plug 87, causes a similar rotative movement of pin 88. However, because of the cam slot 86, tubular member 85, which is prevented from rotating by its attachment to connecting means 84, is caused to travel longitudinally along plug 87.

In the position shown, tubular member 85 is at the extreme left of its travel, slide means 76 is at its extreme left position, and indicating means 91 has been rotated to its clockwise ex-

treme. Counterclockwise rotation of 91 will cause a reverse movement of tubular member 85 and slide 76 thus tending to disengage wedge edge or face 82 from notch 67; this disengaging operation being completed by the adjustment of means 91 to its vertical or neutral position. Further counterclockwise rotation of means 91 then causes an engaging of wedge face 81 with notch 64, the engagement being completed as 91 is turned to its extreme counterclockwise position.

Connecting means 84 is slidably guided relative to section 13 of housing 11 by a suitable pin 92 extending through a slot 93 in said means 84. A slide means 94, guided by a suitable opening 95 in member 90 and also by a slot 96 engaging pin 92, is arranged to directly engage lever 23. A downwardly extending angular portion 97 of member 94 has an opening 98 therein arranged to register with and to slide over means 91 when the said means 91 is turned to its vertical or neutral position. The said means 91 is permitted to turn to positions other than neutral only when means 94 is at its left extreme because of necked-down portion 99 of means 91 being located to align with portion 97 of means 94 when said portion is at its extreme left position. Thus, in the position shown, member 94 cannot be shifted in either direction because notch 98 of portion 97 is in registry with the necked-down portion 99 of 91 but 91 is not in registry with opening 98. The necked-down portion 99 of member 91 is thus so arranged that member 94 must be adjusted to its left extreme, wherein it has no effect on lever 23, before means 91 can be adjusted for either a heating or cooling sequence.

While it is believed that the present invention is clearly disclosed, it will now be briefly described in terms of its operation.

Operation

In the position shown, it is noted that indicating means 91 is directed toward "Heating," hence it is assumed that the apparatus of mechanism 25 is adjusted to control blades 16 and 17 in response to a conventional heating cycle. Thus, the blades 16 and 17 should be opened when more heat is desired and closed when less heat is desired. As a consequence of this adjustment of 91, tubular portion 85 is at its left extreme, slide means 76 is adjusted to its left extreme, and wedge-shaped portion 82 of the said slide 76 is in mating engagement with notch 67 of link means 66, thereby holding the said link means fixed against vertical movement. Therefore, lever 23 is effectively pivoted at 68 and movement upwardly of shaft 31, due to an increase in pressure and a consequent increase in pressure causing an expansion of bellows 32, will result in a clockwise movement of lever 23 and a consequent closing of blades 16 and 17. As a rise in temperature in the space being treated will result in additional pressure being generated in bulb 35, it follows that a suitable increase in pressure in bulb 35 will expand bellows 32 and move shaft 31 upwardly to thereby rotate lever 23 about pivot 68 and close blades 16 and 17 to thereby decrease the supply of heat. This will tend to restore the temperature conditions in the space to normal.

The control point in this instance, as shown, is rather high as is evidenced by the adjusting and indicating means 55 being near the high point of the scale plate 57 and as indicated by pivot means 46 being relatively near shaft 31. As pivot means 46 is moved adjacent shaft 31,

the leverage ratios of lever means 44 are favorable to weight 41 in its opposition to bellows 32 hence a relatively high pressure is required at bellows 32 to overcome the effect of weight 41. 5 When the indicating and adjusting lever 55 is moved to the left along scale plate 57, or to a position for a lower control point, this will result in a clockwise movement of arm 52 (in Figure 4). This causes a consequent movement of pivot 10 means 46 to the right along lever means 44, wherein, as previously noted, it is obvious that the leverage ratios are made less favorable for weight 41 to oppose bellows 32, hence a lower pressure in bellows 32 is able to cause upward 15 movement of shaft 31 against the resisting effort of the weighted lever 44. Therefore, the pressure generated in bulb 35 by a lower temperature is able to cause operation of damper blades 16 and 17, thus establishing a lower control point.

With the apparatus in the position shown, and with indicating means 91 turned to its clockwise extreme, it is obvious that member 94 cannot be moved either to the right or left because notch 98 in the same is unable to slide over 91 beyond the limits of necked-down portion 99. However, when 91 is turned vertically to its neutral position, then 94 may be pushed inwardly and move lever 23 in a clockwise direction. It will be noted that movement of indicating means 91 to its vertical and neutral position not only lines up 91 with notch 98 so that member 94 may be pushed inwardly, but it also advances tubular portion 85 to the right due to operation of pin 88 in slot 86. The movement of 85 to the right causes a consequent movement of slide means 76 to the right thus disengaging wedge portion 82 from notch 67, as previously described, and, in the neutral position, wedge portion 81 is not advanced far enough to the right to engage notch 64 of link 63. Therefore, both links 63 and 66 are free to move without restriction from the slide means 76 and lever means 23 is therefore free to move in a clockwise direction upon being operated by the said member 94. Movement of 94 inwardly, or to the right, causes a clockwise movement of lever 23 and results in a closing of damper blades 16 and 17, as will be obvious upon inspection.

A further counterclockwise rotation of means 50 91 to its extreme, or to its "Cooling" position, results in a further travel of tubular member 85 to the right, and a consequent movement of slide means 76 resulting in a mating engagement of wedge means 81 with notch 64 of link 63, thereby causing a restraining of the said link 63 and permitting rotation of lever means 23 about pivot 65. When lever 23 is pivoted about 65, and upward motion of shaft 31 will result in a counterclockwise rotation of lever 23, thus opening shutter blades 16 and 17 and whereas, as before described, a downward movement of shaft 31 will cause a clockwise rotation of lever 23 and a consequent closing of the said blades. As will be obvious, a relatively high temperature in the space being treated during a cooling cycle requires a relatively large flow of air hence it is quite proper that the relatively high pressure due to bulb 35 which causes an expansion of bellows 32 and an upward movement of 31, adjusts blades 16 and 17 to their open position. Likewise, as the temperature in the space falls, the pressure exerted by bulb 35 on bellows 32 is less, shaft 31 is moved downwardly by the effect of weight 41, and lever 23 is rotated clockwise about pivot 65 thus closing blades 16 and 17 and

decreasing the flow of air. Thus the present apparatus is seen to operate properly for either heating or cooling control, has an adjustable control point for either sequence, and may be manually closed.

While the present invention has been rather specifically disclosed, it will be obvious that many substitutions and equivalents can be used in the practice of the said invention. Therefore, it is intended that the scope of this invention be determinated only by the appended claims.

I claim:

1. In an air outlet control including damper means, means for operating said damper means comprising, in combination, a reciprocable shaft, temperature responsive means for reciprocating said shaft, spaced parallel reed means for guiding said shaft, lever means pivotally mounted on the said shaft and having a weight at one end, pivot means longitudinally adjustable along the other end of said lever means for varying the effectiveness of the said weight in opposing the said temperature responsive means, additional lever means pivotally mounted on said shaft, said additional lever means including a pair of laterally extending oppositely disposed crank portions, depending link means pivotally mounted on each of said crank portions, bearing means mounted between the inner edges of said link means, oppositely disposed V-notches formed in the outer edges of said link means, the vertical dimension of the said notches at their outer edges being at least equal to the normal vertical travel of the said shaft, transversely adjustable oppositely disposed V-shaped members arranged so that one member, the other member or neither member may interengage with the corresponding notches to hold the respective link means stationary and thus cause the said additional lever means to pivot about the interengaged link means, means for shifting the said V-shaped members into or out of engagement with the respective link means, and means connecting the said additional lever means to said damper means for operation thereof.

2. In an automatic register, in combination, means for controlling airflow, movable shaft means, guide means for said shaft means, temperature responsive means for moving the said shaft means, lever means pivotally mounted on said shaft means, link means pivotally mounted on said lever means on opposite sides of the pivotal mounting of the said lever, wedge-like means for centering and locking one or another of said link means against movement, means for controlling said locking means, and motion transmitting means connecting said lever means in operative relation with said airflow controlling means.

3. In control apparatus, in combination, means for controlling a medium, a movable member, condition responsive means for moving said member to various positions, lever means pivotally mounted on said member, additional pivot means for said lever means arranged on opposite sides of the pivotal mounting of said lever means, clutch means having wedge-like surfaces attached to each of said additional pivot means, means for selectively engaging, forcing to a predeter-

mined position and restraining said clutch means so that one or another of said pivot means may be restrained, and means connecting said lever means in operative relation to said controlling means.

4. In control apparatus, in combination, movable means for controlling a medium, a movable member, condition responsive means for moving said member to various positions, lever means pivotally mounted on said member and having a plurality of additional pivot means on opposite sides of the pivotal mounting, means for operatively connecting said lever means to said controlling means, manually operable means for selectively restraining neither or one or another of said additional pivot means, manual means operable to adjust said movable means, and interengaging latch means arranged to permit manual adjustment of said movable means only when said manually operable means is adjusted so that neither of said additional pivot means is restrained.

5. In control apparatus, in combination, means for controlling a medium, a reciprocable member, means for exerting force on said member in one direction, means including a pivotal lever for exerting force on said member in an opposite direction, means for shifting the pivot of said lever to vary the effect of the means including said lever on said member, additional lever means pivoted to said member, means linking said additional lever means to said controlling means, and means for selectively causing rotative motion of said additional lever means in one direction or another upon said member being moved in one direction due to a change in the resultant of the forces acting on the same.

6. In a control device, means for controlling the flow of a condition changing medium, a movable member, condition responsive means for moving said member to various positions, a lever means pivotally attached to said member and connected to said controlling means, said lever including a pair of oppositely disposed crank portions, link members attached to each of said crank portions, bearing means engageable by a portion of each of said link members, each of said link members having a notch with inclined surfaces facing away from the bearing engaging portion of said link member, and a pair of stop means having surfaces adapted to mate with said inclined surfaces and thereby positively position and restrain one or another of said link members so that the restrained link member fixes a pivot about which said lever means may pivot as said movable member is moved.
